CLAIM

The ornamental design for a handle, as shown and described.

DESCRIPTION

FIG. 1 is an isometric view of a first embodiment of a handle incorporating my new design;

FIG. 2 is a top plan view thereof;

FIG. 3 is a bottom plan view thereof;

FIG. 4 is a left side elevation view thereof, the right side elevation view being a mirror image thereof;

FIG. 5 is a front elevation view thereof;

FIG. 6 is a rear elevation view thereof;

FIG. 7 is an isometric view of a second embodiment of a handle incorporating my new design;

FIG. 8 is a top plan view thereof;

FIG. 9 is a bottom plan view thereof;

FIG. 10 is a left side elevation view thereof, the right side elevation view being a mirror image thereof;

FIG. 11 is a front elevation view thereof; and,

FIG. 12 is a rear elevation view thereof.

The broken lines shown represent portions of the handle that form no part of the claimed design

1 Claim, 4 Drawing Sheets
